UNITED STATES PATENT OFFICE.

ANDREW BROWN HYDE, OF POMFRET CENTRE, CONNECTICUT.

FOUNTAIN-PEN.

SPECIFICATION forming part of Letters Patent No. 426,021, dated April 22, 1890.

Application filed October 23, 1888. Serial No. 288,989. (No model.)

To all whom it may concern:

Be it known that I, ANDREW BROWN HYDE, of Pomfret Centre, county of Windham, and State of Connecticut, have invented a new 5 and Improved Fountain-Pen, which carries the ink in the pen-holder and delivers it automatically to the pen in writing.

The following is a full, clear, and exact description.

10 In the drawings, Figure 1 is a top view in section of the whole instrument, showing the feeding-tube *c* on the convex surface of the pen *b*, and the protecting-cap *g*. Fig. 2 is a side view of the feeding-tube *c*, conveying the ink from the pen-holder *a* to the pen *b*, and showing the cuts *h*, which make it flexible. Fig. 3 is a plan view of the feeding-tube *c*, showing that part which comes in contact with the convex surface of the pen *b*, Fig. 1, 15 and showing the ink-opening *i*, through which the ink escapes to the pen *b*, and the cuts *h*, which make it flexible. Fig. 4 is a sectional view in the line *xx* of Fig. 1. *j*, Fig. 4, is the air-hole which admits the air to the pen-holder *a* as the ink is withdrawn from it. Fig. 5 is a side view in section of the whole instrument, showing the feeding-tube *c* placed under the concave surface of the pen *b* and the air-hole *j* above the convex surface of the 20 pen *b*. *g*, Fig. 5, is the protecting-cap, which fits onto shoulders *a²* and *a'*. Fig. 6 is a sectional view in the line *xx* of Fig. 5. The letters of Fig. 6 represent the same parts as shown in Fig. 5. Figs. 7 and 8 are feeding-25 tubes *c*, to be used on both Figs. 1 and 5; but they differ from Fig. 3 by having the cuts *h* arranged on one side of the feeding-tube and the ink-opening *i* arranged on the other side of the feeding-tube. Fig. 7 is a side view of the feeding-tube *c*, showing the cuts *h*. Fig. 30 8 is a top view of the feeding-tube *c*, showing ink-opening *i*, the cuts being on the other side. Fig. 9 is the feeding-tube *c*, the same as Fig. 3, except that the ink-opening *i* is 35 smaller. Fig. 10 is the feeding-tube *c*, the same as Fig. 8, except that the ink-opening *i* is smaller.

a, Fig. 1, is a top view of the pen-holder and reservoir containing the ink, which is 40 held in position mainly by atmospheric pressure and which is delivered automatically to the pen in writing.

b, Fig. 1, is the pen, preferably of gold, to prevent corrosion. This pen *b* is inserted into a slot in the end of the pen-holder *a*, and is 55 thus held firmly in position.

c, Fig. 1, is the feeding-tube, which conveys the ink from the reservoir *a*, Fig. 1, and delivers it through the ink-opening *i*, Fig. 3, to the pen *b*, Fig. 1. This feeding-tube *c* in Fig. 60 1 is placed on the convex surface of the pen *b*. The reservoir and pen-holder *a* unscrews at *e*, Fig. 1, so that it may be filled with ink. The feeding-tube *c*, Fig. 1, is held in position by being fitted into the end of the pen-holder *a* 65 at *d*, Fig. 1, from which it may be easily withdrawn.

If an ordinary tube were placed on the convex surface of the pen *b*, Fig. 1, to deliver the ink to the pen, such a feeding-tube would be 70 inflexible and would interfere with the vibration of the nibs of the pen in writing. Therefore a device is necessary to prevent this.

Fig. 2 is a side view of the feeding-tube *c*, showing a series of cuts *h*, which nearly sever 75 the feeding-tube *c*. The object of these cuts *h*, Fig. 2, is to render the feeding-tube *c*, Figs. 1, 2, and 3, flexible, so that when the nibs of the pen *b* are vibrated in writing the feeding-tube *c*, Figs. 1, 2, and 3, will readily bend up-80ward and then immediately spring back to its former place as soon as the nibs of the pen are allowed to come together. The cuts *h* are not visible in Fig. 1, because it is a top view.

Fig. 3 is the feeding-tube *c* inverted, so as 85 to show that part of it which lies next to the convex surface of the pen *b* in Fig. 1. Fig. 3 also shows the ink-opening *i*, through which the ink escapes in passing from the feeding-tube *c* to the nibs of the pen *b*. 90

The withdrawal of the ink in writing creates a vacuum in the reservoir *a*; but this vacuum is relieved by small bubbles of air, which pass into the reservoir *a* through the air-hole *j*, situated in the end of the reservoir 95 *a* which is nearest the pen *b*.

Fig. 4 is a sectional view on line *xx* of Fig. 1. *a*, Fig. 4, is the pen-holder and reservoir.

b, Fig. 4, is the pen.

c, Fig. 4, is the feeding-tube.

j, Fig. 4, is the air-hole, which may be formed in the material of the pen-holder *a*.

The cap *g*, Fig. 1, fits over the pen *b* and onto a shoulder *a²* to prevent the ink on the

20 distance from the concave surface of the pen *b*, and the part of the feeding-tube which comes in contact with the nibs of the pen *b* is close up against the nibs of the pen *b*. The end of the feeding-tube *c*, Fig. 5, which comes 25 in contact with the nibs of the pen *b* presses constantly against the nibs. This pressing against the nibs is caused by the oblique position of the feeding-tube *c*, Fig. 5. Therefore, when the nibs of the pen *b*, Fig. 5, spring upward, the feeding-tube *c* springs upward, and when the nibs of the pen *b* spring downward the said nibs press the feeding-tube *c* downward. Thus the feeding-tube *c*, Fig. 5, which is placed under the concave surface of the pen *b*, is made to vibrate up and down with the vibration of the nibs of the pen *b* when placed on the convex surface of the pen in 30 Fig. 1.

Fig. 6 is a sectional view in line *xx* of Fig. 5. 40 In Fig. 6 *a* is the pen-holder and reservoir; *b*, the pen; *c*, the feeding-tube placed under the concave surface of the pen *b*; and *j*, the air-hole placed over the convex surface of the pen *b*. This air-hole *j*, Fig. 6, may be formed 45 in the material of the pen-holder *a*. It is evident that when the nibs of the pen *b*, Fig. 1, are pressed upward in writing, that part of the cuts *h*, Fig. 2, which lie next to the pen *b* are sprung a little further apart, and when 50 the nibs of the pen *b* descend the cuts *h*, Fig. 2, assume their ordinary shape, as shown in the drawings.

In Figs. 7 and 8 the ink-opening *i* is arranged on one side of the feeding-tube *c*, and the cuts are on the other side. Of course in 55 Figs. 7 and 8 the ink-opening is next to the pen *b*, Figs. 1 and 5. When the feeding-tube *c*, Figs. 7 and 8, is sprung by the nibs of the pen *b*, Figs. 1 and 5, the cuts *h*, Fig. 7, are 60 pressed nearer together. The cuts *h*, if arranged as in Figs. 7 and 8, should be wider than if arranged as in Fig. 3, because if not wider, in springing the feeding-tube the cuts would come together and might impair flexibility.

65 It is evident that the feeding-tube *c* may be made of several different shapes—such as

pen *b*, Fig. 5, and the feeding-tube *c*, to prevent it from approximating too near the nibs of the pen *b*. This piece of wood, or other suitable material, will not prevent the feeding-tube *c* from springing up and down with the vibration of the nibs of the pen *b*. 90

The cuts *h* of the various figures might be used to allow the ink to escape from the feeding-tube to the nibs of the pen and the ink-opening *i* dispensed with entirely. In fact, some of the ink does escape through these cuts *h*. 95

The ink-opening *i* may be of various sizes—such as long or short, wide or narrow—with 100 out materially departing from the invention, and I do not wish to be limited to any one of these particular dimensions.

Fig. 9 is the same as Fig. 3, except that the ink-opening *i* is shorter. 105

Fig. 10 is the same as Fig. 8, except that the ink-opening *i* is shorter.

I am aware that feeding-tubes for fountain-pens have been known before my invention, one having been patented by George F. 110 Hawkes, October 17, 1865, No. 50,470. In this invention there is employed a rigid feeding-tube, which is greatly enlarged where it comes in contact with the concave surface of the pen. This tube is shoved toward the reservoir to shut off the supply of ink, and is pulled toward the nibs of the pen to turn on 115 the supply of ink.

I am also aware that a patent was granted to John Blair, October 20, 1885, No. 328,454, 120 in which a stiff feeding-tube placed on the concave surface of the pen is made to spring by being set in a flexible rubber socket.

I am also aware that a patent was granted to F. C. Brown, July 13, 1886, No. 345,411, in 125 which a bar is used to convey the ink from the reservoir to the pen. This bar is furnished with longitudinal grooves on both its upper and under surfaces. The groove on the under surface assists in conducting the ink from the reservoir. The groove on the upper surface assists in conducting the ink from the nibs of the pen to the reservoir when the instrument is held with the pen uppermost in con- 130

sequence of too much ink being on the pen. On the end of this bar nearest the point of the pen is a number of transverse grooves called "retarding-ducts," which prevent the ink from flowing too freely. It is evident that this bar must be made considerably thicker in order to accommodate these longitudinal grooves. This making of the feed-bar thicker on account of the grooves cannot, therefore, render the feed-bar flexible in the manner that my cuts *h* make my feeding-tube *c* flexible; but, on the contrary, the thickening of Brown's feed-bar to accommodate the longitudinal grooves makes his feed-bar much more rigid than it would be if such grooves should be entirely omitted.

I do not claim such constructions as those of Hawkes, Blair, and Brown.

Having fully described my invention, what I claim, and desire to secure by Letters Patent, is—

1. In a fountain-pen, the feeding-tube *c*, having cuts *h*, which make it flexible, so that it may spring up and down with the vibration of the nibs of the pen *b*, substantially as described, and for the purpose set forth.

2. In a fountain-pen, the combination, with a reservoir *a*, pen *b*, cap *g*, and air-hole *j*, of a feeding-tube *c*, having transverse cuts *h*, and a longitudinal ink-opening *i*, substantially as described, and for the purpose set forth.

ANDREW BROWN HYDE.

Correction in Letters Patent No. 426,021.

It is hereby certified that in Letters Patent No. 426,021, granted April 22, 1890, upon the application of Andrew Brown Hyde, of Pomfret Centre, Connecticut, for an improvement in "Fountain-Pens," an error appears in the printed specification requiring the following correction, viz: On page 2, in line 36, the words *as it vibrated* should be inserted before the word "when;" and that the said Letters Patent should be read with this correction therein that the same may conform to the record of the case in the Patent Office.

Signed, countersigned, and sealed this 6th day of May, A. D. 1890.

[SEAL.]

CYRUS BUSSEY,
Assistant Secretary of the Interior.
